(57) **CLAIM**

The ornamental design for a message board set, as shown and described.

DESCRIPTION

FIG. 1 is an isometric view of an message board set showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof;

FIG. 7 is a bottom plan view thereof; and,

FIG. 8 is an operational view showing the message board set mounted to a disabled vehicle.

The broken lines in FIG. 8 illustrate a disabled vehicle, which is environment and forms no part of the claimed design. The broken lines in FIG. 3 represent portions of the message board set that form no part of the claimed design.

1 Claim, 4 Drawing Sheets
